PUNCHING APPARATUS FOR SHEET OR
STRIP MATERIAL

Robert H. E. Schlecht, Afton, Mo.

Application April 20, 1949, Serial No. 88,669

17 Claims. (Cl. 164—89.5)

1

This invention relates to punching apparatus for sheet or strip material and the like, and has particular reference to an automatic punch or perforator device of novel construction and effective and positive operation, for punching or perforating paper, leather, cloth and other materials including relatively soft metals and the like, which are suitable to punching operations.

In general, it is the purpose of the present invention to afford a highly compact and readily portable punch device of electromagnetically operated, impact drive character for automatic punching of materials, wherein the device embodies control provisions of novel character certain of which are under direct regulatory control of the operator.

In line with the foregoing general statement, it is an important object of the present invention to provide an automatic punch device of a novel and highly effective character, which is operable selectively, for producing in materials of the character indicated, punchings or perforations of regular or irregular spacing and in any predetermined or desired design or pattern.

Another important object of the invention is to provide a readily portable punch device of novel and compact construction, which is adapted for multiple punching automatically in response to step-by-step or walking advance of the device in any direction over the surface of the material to be punched.

A further object is to provide an automatic punch device in which the displacement speed and force of the punching element in punching operation, are controllable within relatively wide limits, whereby the device may be regulated for perforating materials differing in thickness and resistance to punching.

A further object is to provide an automatic punch device which is fully operable to produce complete and clean-cut perforations in materials of the character indicated, and which is capable of producing indentations or imprints in surfaces of metallic or non-metallic materials, where imprinting rather than perforating is desired, as for example, in center-punching or marking preparatory to drilling or material cutting operations.

Yet another object is to provide a punch device having a reciprocable punch member and embodying electro-magnetically operated means for reciprocating the member in material punching operation, wherein said means produces punching displacements of the member by impact action relative to the member, whereby to

2

assure positive imprinting or clean-cut perforating of the material under punch.

Still another object is to provide an automatic punch device having a reciprocal punch member capable of movement angularly relative to its axis of reciprocation, wherein angular movement of the member is produced by advance of the device while the member is still in contact with the material punched following the punching stroke, and such angular movement initiates a cycle of operation including retraction of the punch member from the material, return of the member to its reciprocal axis, and thence a punching stroke of the member. The cycle is repeated at each advance of the device over the surface of the material undergoing perforation thereby.

A still further object is to provide an automatic punch device operable cyclically as indicated in the foregoing object, which includes a control provision regulatable for determining initiation of the cyclic operation in response to angular movement of the punch member to a greater or lesser extent, whereby the spacing of successive perforations produced by cyclic operation of the device, may be determined as desired.

The foregoing objects and numerous other objects and advantages of the present invention, will appear from the following description of a presently preferred embodiment thereof as illustrated in the accompanying drawing, wherein:

Fig. 1 illustrates in vertical sectional elevation, the present novel punch device;

Fig. 2 is an enlarged, fragmentary section of the device, as viewed from line 2—2 in Fig. 1;

Fig. 3 illustrates in front elevation, the control switch assembly of the device;

Fig. 4 is a fragmentary sectional view similar to that of Fig. 2, but showing the punch member in an angularly displaced position;

Fig. 5 is an enlarged view in perspective, of the lower portion of the device shown in association with material to be punched, illustrating a hold-down provision for retaining the material against lifting with the punch upon retraction of the latter;

Fig. 6 is an enlarged, fragmentary section transversely of the device in the zone of the magnetic hammer, as viewed from line 6—6 in Fig. 1;

Fig. 7 is a circuit diagram of the electrical portion of the device;

Fig. 8 is an enlarged detail view partly in section, of a tip element for the punch member, the element here shown differing from the form of perforating tip element as shown in Fig. 1, in

that it is adapted for material imprinting or indenting, as for marking drill centers, material cutting lines, and the like, and

Fig. 9 is a sectional view of a switch control expedient, as viewed from line 9-9 in Fig. 3.

Referring to the drawing by suitable reference characters, the present novel punch device includes a frame which conveniently to the compactness of the structure, is constituted by a tubular member 10, preferably a single tube of a suitable rigid, non-magnetic material, as brass or the like. Arranged longitudinally in the tube 10 is a rod member 11 of suitable non-magnetic material, as stainless steel or the like, which is reciprocably displaceable in punch operation, as will hereinafter appear. The upper end 12 of the rod is supported and guided in rod displacement, by a plug element 14 seated in the upper end 15 of tube 10, the plug having tube vent openings 16. Plug 14 is retained in adjusted position longitudinally relative to the tube end, by a split-collar 18 embracing the plug in clamped relation thereto, and supported on the tube end 15 as through the collar extension 19 threaded or otherwise connected to the latter. The rod is threaded over its end portion 12, and threaded thereon is a stop member 20 providing a shoulder 21 forming a spring mounting seat for a buffer spring 22, and presenting additionally, an annular flange 23. A lock-nut 24 retains the stop in position on the rod. Buffer spring 22 which serves a purpose later to appear, is substantially concentric of the rod 11 below flange 23, and has its upper end preferably expanded into frictional support on shoulder 21. While not indicated on the drawing, the spring may be secured to shoulder 21 by positive means other than the indicated frictional mounting, as by grooving the shoulder to receive the end turns of the spring. Upward movement of the rod is yieldingly resisted by a spring 26 bearing between the lock-nut 24 and the plug 14 in a recess or socket 27 therein, this spring serving constantly to load the rod in the downward direction of its displacement. A larger, buffer spring 28 carried by the plug 14, has its free end disposed for engagement by the stop flange 23 in the course of upward movement of the rod, the spring when so engaged and compressed, serving thereby to stop further rod displacement in the upward direction, and at the same time, imposing on the rod a force in aid of the downward stroke of the latter.

The lower end of rod 11 is suitably rigidly connected to the upper end of a rod element 30 preferably formed of a hard material such as stainless or tool steel. The rod is enlarged at its upper end, to afford an abutment 31 presenting a top annular surface 32 constituting a striking face or anvil for a punch actuating hammer presently to be described. Rod 30 in its lower end portion, provides a shoulder 34 and a threaded end 35, the shoulder serving several purposes one of which is as a lower guide for the connected rods 11 and 30 in reciprocal movement. Suitably fixed within the lower end portion 36 of frame tube 10, is a tubular element 38, and slidably engaged in element 38 is the shoulder 34, the tube element and shoulder thus cooperating to provide both lateral support and displacement guiding support for the connected rods.

Carried by the rod element 30 in extension below its lower end portion, is a punch rod or stem 39 which projects in exposed position below the lower end 40 of frame tube 10, the stem normally supporting on its lower end 42, a punch or mate-

rial perforating tip element 43 of a character to be described later. The upper or head end of the punch stem 39 is formed to provide a frustoconical enlargement or head 44 with the larger end uppermost, and such end is yieldably retained in engagement with the bottom face of the threaded end 35 of rod 30, by a compression spring 46 having its upper end bearing against the conical surface of head 44 near the larger end thereof, and its lower end bearing against a cap 47 threaded on the rod end 35. Cap 47 is apertured as shown, to accommodate the punch stem in extension therethrough and to permit angular movements of the stem relative to the cap, as for a purpose to appear.

In the presently preferred embodiment of the invention, the movable or reciprocal punch member considered as a unit comprising the rods 11, 30 and stem 39, is actuated by electro-magnetic means including a plunger or armature 50 in the form of a tubular element of magnetic material which is freely slidably received in frame tube 10. At its upper end is a disc 51 centrally apertured to accommodate rod 11, the disc being of hardened steel to serve as a hammer head for engagement with the yieldable abutment or buffer spring 22. A similar hammer disc 52 is carried by the lower end of plunger 50, for striking engagement with face 32 of the rod anvil or abutment 31.

Externally on the tube 10 are electro-magnet coil units 54 and 55 in relative adjacence, the upper coil unit 54 when energized, effecting magnetic attraction of plunger 50 to cause the latter to rise in tube 10 and tend to assume a magnetically centered position relative to the coil unit. The plunger as thus displaced, engages the buffer spring 22 by impact of its hammer head 51 thereagainst, compressing the spring and producing a sudden and rapid elevating displacement of the rod assembly including the punch stem 39. Upward displacement of the rod assembly is arrested by the buffer spring 28 as hereinbefore indicated. On the other hand, energization of the lower coil unit 55 attracts plunger 50, causing downward movement thereof in tube 10 toward a magnetically centered position relative to the coil unit. In so moving, the lower hammer head 52 impacts against the face 32 of the striking abutment 31, and thereby produces a sudden and rapid downstroke of the rod assembly. The plunger-affected downstroke or punching stroke is aided in initial displacement, by expansion of the buffer spring 28 against the rod stop flange 23, and thereafter to a lesser degree by expansion of the spring 26, while the electromagnetically produced downstroke of the hammer is aided by expansion of the buffer spring 22, as this will be now appreciated.

Before turning to the control provisions for determining and regulating punch operation, it is desired here to describe the mounting arrangement of the assembly. The punch device according to the present embodiment, is of a portable character and adapted for manual displacement of the punch device as a whole, in walking manner over the surface of the material to be punched. To this end, there is provided a base ring 56 preferably of the form shown by Figs. 1 and 5, on one side of which is secured an upstanding bracket 58, the bracket having a handle 59 attached thereto as by the headed bolt 60. Projecting from the bracket and centrally over the base ring 56, is a member 62 affording a split-collar 63 to receive the lower end of frame tube 10 in clamped, sup-

porting relation thereto. Through the split collar, the tube 10 may be adjusted vertically relative to the base ring 56. In application, the base ring is rested directly upon the exposed surface of the material to be punched, such material being spread upon a suitable supporting surface, as the top of a work bench or the like. The punch stem 39 and its punching tip 43 thus are located over the portion of the material in the center of the base ring. Included in the base assembly is a tensioning spring 64 (Figs. 1 and 5) arranged to have its coil portion 66 positioned for rest under tension, against the material under punch in the area thereof underlying the punch tip 43, as illustrated more particularly in Fig. 5. The spring not only holds the indicated area of the material in place for punching, but effectively prevents lifting thereof with the punch tip 43 upon retraction of the punch following the perforating operation.

The electrical circuit controls for the coil units 54 and 55 are carried on a panel block here comprised of a brass plate 70 and a face plate 71 of insulating material, secured thereto, the block being mounted directly on the lower end of tube 10 (Fig. 3) by attachment screws 72. On the panel is a main switch comprising opposed stationary contacts 74 and 75 carried on insulating brackets 76 and 78 respectively, suitably attached to the panel. The contact 75 which is adjustable for varying the relative spacing of the opposed contacts, has associated therewith a movable contact 79 on a resilient arm 80 of conducting material. Arm 80 is supported on a movable insulating arm 82, the latter having a hub 83 secured to one end of a shaft or pin element 84 which is rotatably journaled through the lower right hand corner section of the panel (Fig. 3, and also shown in part in Fig. 1). Also on arm 82 is a conductor arm 86 on the end of which is a contact 87 opposed to and cooperable with the fixed contact 74. On the panel near arm 82 is a circuit connector post 88 between which and the movable contact arms 80 and 86, is a flexible lead 90.

Pivoted on a stud 91 fixed to the panel, is an insulating arm 92 which supports at its free end an L-shaped cam element 94 of conducting material, having thereon a contact 95 forming part of a control switch. A finger actuator 96 is pivoted on a stud 98 fixed to the panel, and includes a cam face 100 adapted for engagement with the L-shaped cam element 94, the latter being yieldably biased toward cam face 100 by a curved leaf spring 102 of conducting material, fixed to a conductor arm 103 insulatingly carried on a stud 104 on the panel adjacent the contact bracket 76. Circuit connection between contact 74 on bracket 76 and the spring arm 103 is made preferably by a conductor element 106 fixed to contact 74 and bearing in tension, against the hub portion of arm 103.

A spring contact arm 107 having a contact 108 for cooperation with contact 95, is carried by a member 110 pivoted to stud 91, the contact arm 107 being connected by a flexible or spring-type lead 111, to a circuit-connector post 112 on the panel. Carried by member 110 therebelow, is a block 114 of insulating material, provided with a recessed slot 115 to receive the head end portion of a screw 116 serving a purpose presently to appear. The finger piece 96 has a projection 118 underlying the block 114, operable upon finger depression of the actuator to abut the block and

raise the same. Elevation of the block raises the contact 108 toward contact 95, the latter then being in a position determined by engagement of the cam 94 with an adjustable stop 99. Such depression of the finger piece thus effects engagement of the contacts, which initiates punch operation as will hereinafter appear.

As shown by Figs. 3 and 9, the stop 99 comprises a block preferably of inverted U-shape, 10 formed of fiber or other suitable insulating material and adjustably positioned on the panel face by the stud 98, the latter extending between the legs of the U-shaped block. A shoulder-forming flange 93 carried by or formed integrally of the stud 98, serves to clamp the stop 99 in adjusted position on the panel such that its upper rounded end 97 is disposed for engagement by the L-cam 94 when the finger piece 96 is in a neutral position, or depressed as hereinabove described. 15 Moreover, the flange 93 provides a friction seat for the pivotal finger piece 96, the latter being urged thereagainst under the tension of a suitable spring such as the spring washer 101 engaged beneath the head of a screw element 105 threaded into the end of stud 98 as shown in Fig. 9. By present preference, the stud 98 is threaded through the panel and is held by a lock nut 109.

The neutral position of the finger piece 96 as 20 above referred to, is that in which the cam surface 100 of the piece is clear of the L-cam 94 such as to permit the latter to engage upon the end 97 of stop 99, while the projection 118 of the piece is near to but out of contact with, the block 25 114. When the parts are so disposed, the contacts 95 and 108 will be separated by a relatively small gap. Moreover, such contact separation in the neutral condition of the control, may be increased or decreased by adjusting the position of 30 stop 99.

Returning to the main switch at the right hand side of the panel, the shaft or pin 84 extends through and outwardly beyond the rear of the panel, and has secured thereon an adjustably extensible lever 119 which has its end 120 turned for projection through an opening 122 provided through the side of frame tube 10 and the upper end section of the tubular member 38 (Fig. 1). The terminal portion of lever end 120 is rounded as shown, for cooperation with a switch actuator 123 slidably in the bore of member 38, actuator 123 having a slot 124 to receive the lever terminal portion, as illustrated in Fig. 1. The upper end of the actuator is formed to provide a flange head 126 which in the lowered position of the actuator, rests upon the upper end of the member 38 (Fig. 2). Upward displacement of the actuator is limited by a finger element 127 extending inwardly from a bracket 128 removably secured externally on the tube 10 by screws 130, the finger projecting into a slot 131 in the side of the actuator substantially opposite the slot 124. When the punch rod assembly is lowered or at the end of its punch stroke, as shown in Fig. 1, the actuator is lowered to admit the lever terminal in the slot 124, the lever being loaded in the direction to insert its terminal in the slot, by a suitable means such as the tension leaf spring 132 arranged between the lever and an abutment 134 preferably projecting from the rear side of the panel block. In such position of the lever, the movable contact 87 of the main switch will be in engagement with fixed contact 74.

Now upon upward or punch retracting displacement of the punch rod assembly, the shoul-

der 34 of rod element 30 engages the lower end of the actuator 123, elevating the same with the punch rod assembly, and thereby effecting through lever engagement by the lower inclined cam end 135 of actuator slot 124, pivotal displacement of the lever in the clockwise direction as viewed in Fig. 1. The lever when so moved, opens the contacts 74—87 and engages the movable contact 79 with the fixed contact 75, and at the same time, the lever terminal end bears against the side of actuator 123 below the slot 124, and thereby tends to maintain the elevated position of the actuator in consequence of lever tensioning by spring 132. Accordingly, in order to assure return of the actuator upon the down-stroke or punching stroke of the rod assembly, there is here included in the rod assembly, means for effecting actuator return. Sleeved on the rod 11 and within the plunger 50, is a non-magnetic member 136 which may be here termed a trigger plunger, the same being formed at its lower end to provide a plurality of forwardly extending fingers 138 which project through openings 139 (Fig. 6) in the bottom hammer disc 52 of the armature plunger (Figs. 1 and 6). The trigger plunger is capable of limited axial movements relative to the armature, being confined by the armature discs 51 and 52 such that it follows armature displacements without retraction of the fingers 138 from the disc openings 139. The trigger action of the member 136 occurs at the end of the punching stroke of the rod assembly when downward movement of the armature 53 stops. As such time, the trigger plunger continues downwardly in the armature in consequence of its downward movement, to extend its fingers 138 through disc openings 139 and bring them into striking abutment with the head flange 126 of the actuator 123. The actuator in reaction to such impact, is thereby forced downwardly until the terminal end of the switch operating lever 119 again enters the actuator slot 124, and thereby opens contacts 75—79 and closes contacts 74—87.

Fig. 7 illustrates the circuit arrangement of the coil units and control switches as now described. As there appears, a lead 150 from one end of the upper coil unit 54, and a lead 151 from one end of the lower coil unit 55, are joined in connection to one side 152 of a supply line leading from a suitable electric power source (not shown) which may be 110 volt, 60 cycle mains. The other end of the lower coil unit 55 is connected by a lead 154 to a control resistor unit or rheostat 155, the rheostat in turn having a connection by lead 156 to the contact 75 of the main switch. Extending from the opposite side of the upper coil 54 is a lead 158 which is connected to the contact 108 of the control switch, through the switch connector post 112. The other contact 95 of the control switch is connected to main switch contact 74 in the manner already described, as through spring 102, arm 103 and element 106, the latter connection being indicated in Fig. 7 by the reference numeral 157. The opposite side 159 of the supply line, is connected to the post 88 which is in circuit with contacts 79 and 87 through lead 80 and the switch arms 80 and 86, as before described. Preferably, a condenser 160 is arranged across each of the main switch contact sets 74—87 and 75—79, to dampen contact arcing. While the rheostat 155 and the condensers 160 are shown only in the circuit diagram, it is to be understood that in practice, these are mounted on the punch device, as for example,

on a side of the coil assembly, whereby to complete the fully portable character of the punch.

Describing now the provision for effecting automatic operation of the device in response to advance or walking of the device over the material to be punched, the screw 116 having its head end in the slot 115 of block 114 attached to the structure carrying the control switch contact 108, is extended together with a spacing sleeve 162 thereon, through the panel block and through a slot 163 in the lower end of frame tube 10 (Figs. 2 and 4). The inner threaded end of screw 116 is threaded into an opening in a wall of a cup-shaped member 164. Member 164 is telescoped over the lower reduced end 166 of the guide member 38 fixed in the tube, and is loaded downwardly by a spring 167, to engage its bottom wall 168 against the upper face 170 at the larger base end, of a frusto-conical element 171 hereinafter referred to for convenience, as the movable cone of the mechanism. The conical face 172 of the movable cone engages the internal conical face 174 of a fixed annular cone element 175, the latter being secured in the bottom end of the frame tube 10, as by the threaded connection shown. Cone 175 has openings 176 to vent the tube 10 in its lower end portion. In the present example, the angle of the conical faces 172 and 174 is approximately 45 degrees to a diametral plane of the tube 10, whereby to facilitate sliding movement of the movable cone relative to the fixed cone. Movable cone 171 has a central or axial bore 176 of a diameter to accommodate angular movements of the punch stem 39 in extension therethrough, and is formed further, to provide a relatively thin annular flange 178 in the upper end of bore 176, presenting a smoothly rounded margin disposed relatively closely about the stem 39.

When with the parts positioned as shown in Fig. 2, the stem 39 is displaced angularly from the axis of punch displacement, as for example toward and to the limit shown in Fig. 4 wherein the stem abuts the lower margin of the conical face 174 of fixed cone 175, the stem engages the rounded margin of flange 178 and urges the cone 171 to one side, causing the cone to slide up one side of the conical face 174 of lowered fixed cone 175. Stem 39 rocks on the rounded margin of the flange and because of its angular relation thereto, tends to lift the cone. However, the spring-pressed cup member 164 having its bottom wall 168 in contact with the upper face 170 of the cone, opposes and tends to balance the cone lifting action of the stem such as to relieve the bearing pressure of the upper cone against the lower cone, whereby the upper cone 171 moves smoothly and easily up the side of the lower cone as the stem is angularly displaced.

As the cone 171 is thus elevated, it raises the cup member 164 and the latter, through the screw 116, correspondingly raises the block 114. The resulting elevation of the block 114 brings control switch contact 108 toward the upper companion contact 95 for engagement therewith to complete the punch actuating circuit controlled by these contacts. The extent of angular movement of stem 39 necessary to produce engagement of the contacts, is determined by the operator through location of the member 96 either in its neutral position wherein cam 94 rests on stop 99, or in an elevated position to engage the cam face 100 with the contact cam element 94 such as to locate the contact 95 in a position of greater or lesser elevation relative to the contact 108

when the latter is in its initial lowered position. The foregoing serves a purpose presently to appear.

When stem 39 is released for return to its normal vertical position, the cone 171 is returned by the spring-loaded cup 164 to its centered position on fixed cone 175 (Fig. 2). As this occurs, the flange 178 bearing against the stem, serves in conjunction with the spring 46 acting on the head 44 of the stem 39, to effect positive return of the stem to its vertical position. The action is further facilitated by the upward displacement of the stem which is effected at such time, as this will appear presently.

It is desired to emphasize here that with the exception of the hammer assembly 50-51-52 and the springs including springs 22, 26 and 28, substantially all metallic elements of the punch assembly within the frame tube 10 or otherwise near the effective magnetic fields of the electromagnetic coil units, are provided of suitable non-magnetic material, as stainless steel or the like. This is adhered to in the present structure in order to avoid magnetic leakage or dissipation of the magnetic forces which if permitted, would seriously impair or reduce the magnetic power of the device.

Describing now the operation of the present novel punch device, upon placement of the device on the surface of the material to be punched and assuming connection has been made to the electric power source, the operator pivots the finger actuator 96 in the counterclockwise direction as viewed in Fig. 3, to bring the projection 118 into lifting engagement with block 114. Upward movement of block 114 thereupon elevates contact 108 toward contact 95 until the contacts are engaged. Since the reciprocal punch mechanism is normally lowered in the de-energized condition of the punch device, the parts thereof will appear as in Fig. 1, with the bottom end of the punch tip element 43 resting on the material to be punched, and with the lever 119 located as shown, to close contacts 74-87 of the main switch. Consequently, upon engagement of contacts 95-108 of the control switch, the energizing circuit of the upper coil unit 54 will be completed (Fig. 7), thereby effecting magnetic attraction of the plunger 50 to effect upward displacement of the punch rod assembly in the manner hereinbefore described. As this occurs, the resultant elevation of the switch actuator 123 produces outward pivoting of the lever 119 to cause opening of contacts 74-87 and closure of contacts 75-79, the latter completing the energizing circuit of the lower coil unit 55. It is to be noted in connection with the foregoing, that in the upward magnetic attraction of the plunger 50, the plunger moves rapidly into striking abutment of its head disc 51 with the buffer spring 22, thereby producing a quick impact lift of the rod assembly which following a punching stroke, effects a positive retraction of the punch tip 43 from its perforating embedment in the punched material. Moreover, actuation of the main switch lever 119 at this time, is delayed such as to permit full retracting displacement of the rod assembly. The delay here is effected as a result of the relative spacing of the rod shoulder 34 and the lower end of the actuator 123 which obtains at the end of the punch stroke, as shown in Fig. 1, since such spacing requires that the rod assembly be retracted to an appreciable extent before shoulder 34 engages and elevates the actuator 123.

Now upon energization of the lower coil unit 55, the plunger 50 is attracted rapidly downward, causing its lower head disc 52 to strike or effect a hammer-like blow against the face 32 of the hardened anvil or abutment element 31 on the rod 30 of the punch rod assembly. Such produces impact displacement of the rod assembly downwardly in its punching stroke, which thus effects with considerable force, punching or perforating entry of the tip 43 in or through the material under punch. In the punching stroke, the rod or stem 39 is maintained vertical in axial coincidence with the longitudinal axis of the rigidly connected rods 11 and 30 thereabove, through the loading spring 46 acting on the stem head 44 in a manner yieldably to force its large end face into full contact with the bottom face of the end portion 35 of rod 30. As so maintained, the stem moves in a straight line toward the material in the punching stroke of the device, which thus facilitates the attainment of clean-cut perforations. At the end of the punching stroke, the trigger plunger 136 effects return of the switch actuator 123 in the manner hereinbefore described, and thereby causes actuation of the main switch to open contacts 75-79 and close contacts 74-87. Whereupon punch retraction again takes place, with the operation continuing through the cycle described, so long as the finger piece 96 is held depressed such as to maintain block 114 raised and the control contacts 95-108 closed. With the punch operating automatically as indicated, the operator may repeatedly lift the whole punch device and re-deposit it on the material to be punched, thereby effecting successive perforations in any desired pattern or design. It is to be noted here that the operator is aided appreciably in effecting movement of the punch device from point to point over the material under punch, by the tendency to upward lift of the device as a whole, consequent to upward electromagnetic displacement of the hammer and its impact engagement with the buffer spring 22 in the cycle of punch operation. This latter effect with its now obvious advantage in operation of the device, is present whether the punch is operated in the manner hereinabove described, or operated by a walking displacement of the device over the material, as will be described hereinafter.

While one or any successive number of perforations may be produced in the manner above noted, the operator may condition the punch device so that it will produce successive perforations merely upon pushing or walking the device over the material in any desired or predetermined direction thereover. To such end, the operator starts the punch in operation as above described, and then pivots the finger piece 96 counterclockwise (Fig. 3) either to its neutral position or to a position elevating the contact 95 through raising of the cam element 94 by the cam face 100 on the finger piece. As this is done, the finger piece projection 118 leaves block 114, releasing the same to its lowermost position as effected by the spring-loaded cup member 164. The resulting separation of the control contacts 95-108, stops punch operation with the punch rod assembly at the end of its punching stroke, wherein the tip 43 is embedded in the underlying material. Now by advancing the punch device such as to slide the base ring 56 along the surface of the material, the stem 39 having its tip 43 embedded in the material consequent to the last punching stroke, will be caused to move

angularly. When so moved, it effects through the cone 171, cup member 164, screw 116 and block 114 actuated thereby in the manner hereinbefore described, an elevation of the contact 108 until the latter engages contact 95. Whereupon, the punch operates to retract the stem 39 from the punched material, with the stem returned to the vertical punching axis in the manner described hereinbefore, and thence to produce a punching stroke. The foregoing automatic action of the punch will be repeated at each advance of the device, so that by walking the punch over the material, successive imprints or perforations will be produced. In the walking operation of the device, the relative spacing of the perforations or imprints may be determined and varied by regulating the position of the control contact 95 through either the stop 99 or the cam 100 of the finger piece 96, this because the position of contact 95 determines the extent to which the punch stem 39 must be angularly moved in order to bring contact 108 into engagement with the contact 95. For example, if contact 95 is set so that contact 108 engages therewith after angular movement of stem 39 to an extent such that the center-to-center distance between the tip 43 embedded in the material, and the point of intersection of the vertical axis of punch rods 11 and 30 with the underlying material, is approximately a quarter of an inch, then successive perforations will appear at substantially quarter-inch space intervals as the device is walked over the material. It is to be noted here that the adjustable stop 99 is employed to determine or set the initial or minimum gap spacing of the contacts 95-108, hence to determine corresponding minimum spacing of the perforations or imprints in the material under punch. This initial gap may be varied of course, by adjusting the position of the stop 99 in the manner hereinbefore noted. Once set to secure the desired contact gap, the punch may be operated with the finger piece 96 in its neutral position, the spacing of the punchings then being uniform and not less than the spacing corresponding to the set gap. On the other hand, materially greater spacing of the punchings are obtainable within relatively wide limits, through actuation of the finger piece 96 to engage its cam surface 100 with L-cam 94 whereby to effect the desired increased separation of the contacts 95-108. The spacing control in the latter case, is effected at the will of the operator and may be accomplished at any time during the operation of the punch on the material under perforating or imprinting treatment.

As indicated objectively herein, the present punch device is suitable for punching many different materials, as paper, cloth, leather and even soft metals. Because such materials differ widely in their punching resistance characteristics, it is desirable to include in the present device means for regulating the force of the punch in its punching stroke, whereby the punching force may be reduced for low-resistant materials where a greater force is not necessary to effect clean-cut perforations, and may be increased in the presence of more resistant materials, or where several layers of the same or different materials are to be perforated at one time. The control resistor or rheostat 155 in the energizing circuit of the lower or punch stroke producing coil unit 55, as shown in Fig. 7, here serves the foregoing purpose. By adjusting the rheostat, 75

the attractive force of the coil unit may be increased or decreased, with consequent corresponding increase or lessening of the impact force of the plunger 50 against the striking abutment 31 of the punch rod assembly, which thus determines a greater or lesser force of the punch in its material perforating function. It is to be noted also, that the foregoing increases and decreases the speed of plunger displacement proportionately to the change in magnetic force, which thus affects the ultimate punching force.

It is desired to emphasize here that the present novel punch device is well adapted for and fully capable of producing not only clean-cut perforations in material of the character herein indicated, but also imprints or indentations in materials suited thereto, including relatively soft metals and the like, such as to mark the materials for subsequent drilling or cutting operations and the like. In either case, the material treatment may extend in any desired or predetermined trend over the material, or in accordance with any line pattern. Accordingly, it is to be understood that unless otherwise expressly stated herein, the terms punch and punching together with references to the punching operation of the device, all as employed herein and in the claims hereunto appended, shall be considered as covering both perforating and indenting or imprinting.

From the foregoing description of the device as illustrated, it will appear now that the present punch device affords a desirably compact and portable unit which may be moved quickly and easily over the material under punch or from one point to another thereon, and from one work table to another as may be desired. While the punch is herein shown and described as a portable unit, nevertheless it will be now appreciated that the unit may be mounted in fixed position relative to a work surface, and the material to be treated displaced over the work surface beneath the punch tip, in the punching operation.

An additional feature of the invention resides in the punch tip element 43 as shown in section in Fig. 1 and in perspective elevation in Fig. 5. As therein illustrated, the tip element is detachably mounted on the free end of the punch stem 39, preferably being secured thereto by a through-pin 200. It is formed to provide a socket 201 to receive the stem against a bottom shoulder 202 of the socket, the bottom 202 transmitting the drive force of the stem to the tip in punching operations. Beyond the socket, the element provides a convergently tapered section 204 of hollow form, terminating in a tubular material-entering end 205. In the tapered section 204 are formed wall openings 206 which afford discharge outlets for the portions of the material cored out by the tubular end 205 in material punching. While the tip is held on stem 39 by the pin 200, it may be frictionally seated on the stem, as by affording a split socket wall and contracting the socket into clamped position on the stem.

The tip element 43 as so constructed including the tubular end 205, is thus adapted for the production of uniform, clean-cut perforations in the material under punch. This action of the tip is in consequence not only of its end formation, but importantly herein, of the character of punch operation, which includes the straight-line, punching stroke travel of the stem 39 and the magnetic plunger-produced, impact drive of the punch rod assembly in its punching displacement.

While the tip 43 of the character shown and described, may be employed in certain instances, in the application of the present punch device to the production of imprints or indentations in material, it is not suited for example, to marking of materials for later drilling or cutting operations. For the latter purpose, a tip element of the form shown by Fig. 8, may be substituted for tip 43. The tip according to Fig. 8, comprises a solid, relatively sharply pointed, substantially 10 conical end section 208, and a hollow tubular shank section 209 split longitudinally at one side, as at 210, the hollow shank presenting a bore 212 terminating in a bottom flange or shoulder 213 for abutment with the end of the stem 39 in tip application to the stem. The bore 212 of the hollow shank may be of a diameter slightly less than the diameter of stem 39, so that in 15 mounting the tip element on the end of the stem, the shank is spread as permitted by the split 210. Spreading of the shank places the wall thereof under tension, such as to cause it to contract and hence grip the stem 39 in assembly thereon. To facilitate tip mounting and removal, the tip element is provided with a transverse hole 214 through which may be inserted a suitable tool, such as a piece of rod, by which the tip may be gripped in forcing it onto or from the stem.

Having now described and illustrated a presently preferred embodiment of my invention, it is to be understood that various modifications may be made thereto without departing from the spirit and full intended scope of the invention as defined in the appended claims.

I claim:

1. In a material punching device, an axially movable rod-like punch member including a punch element adapted at one end for material punching, said punch element being movable angularly relative to the longitudinal axis of the member, relatively spaced abutments on said member, an electro-magnetically actuated hammer movable between said abutments and adapted for impact engagement therewith, the hammer electro-magnetically actuated to impact engagement with one abutment, effecting punching displacement of the member, and electro-magnetically actuated to impact engagement with the other abutment, and means responsive to angular movement of said punch element for effecting electro-magnetic actuation of said hammer for impact engagement with said other abutment, whereby to effect a retracting displacement of the member.

2. In a material punching device, a movable punch member adapted at one end for material punching, a striking abutment on the member, a hammer movable in one direction against said striking abutment for effecting punching displacement of the member, a stop element including an abutment connected to the member, the latter said abutment engageable by said hammer upon movement thereof in an opposite direction, for effecting retracting displacement of the member, a spring element carried by the said stop element and normally extended below the latter said abutment, whereby the hammer yieldably engages the spring element prior to engaging the said abutment incident to retraction of said member, and means including said spring element effective on said member in its retracted position, to impose a force thereon in aid of subsequent punching displacement of the member.

3. In a material punching device, a movable

rod-like punch member having relatively spaced abutments thereon and including a punch element at one end of the member, movable angularly relative to the longitudinal axis of the member, electro-magnetic operating means including a pair of magnet coils and an armature, said armature being movable against one of said abutments in response to energization of one of said magnet coils, for causing movement of said member and punch element in a material punching direction, energization of the other magnet coil causing movement of said armature against the other abutment to produce retracting movement of the member and punch element, and means responsive to angular movement of said punch element, for effecting energization of said other magnet coil.

4. In a material punching device, a rod-like punch member including a punch element, movable to and from a punching position, said punch element being movable angularly relative to the longitudinal axis of the member, a magnetic armature for moving said member and punch element, first and second magnet coils in operative relation to said armature, an energizing circuit for said first coil to energize the same and thereby effect movement of the armature to move said member and punch element toward and into said punching position, an energizing circuit for said second coil, including a control switch therein, and means responsive to angular movement of said punch element, operable to close said switch and energize said second coil, energization of said second coil effecting movement of said armature to move said member and punch element from said punching position.

5. In a material punching device according to claim 4, characterized further by means in the energizing circuit for said first coil, for regulating energization thereof such as to vary the speed and force of the armature in its operation to move said member and punch element toward and into said punching position.

6. In a material punching device, a punch member adapted at one end for material punching, said member being movable to and from a punching position, relatively spaced abutments on the member, an armature movable between said abutments, a pair of magnet coils in electro-magnetic operating relation to said armature, energizing circuit means including a two-position switch, for energizing said coils such that in one position of the switch, one of the coils is energized to cause movement of the armature against one of said abutments, to effect movement of the punch member to the punching position, while in the other position of the switch, the other coil is energized to cause armature movement against the other abutment and thereby effect movement of the punch member from its punching position, and means operable responsive to and in accordance with said movements of the punch member, for actuating said switch from one to the other of its positions.

7. In a material punching device, a punch member adapted at one end for material punching, said member being movable to and from a punching position, relatively spaced abutments on the member, an armature movable between said abutments, a pair of magnet coils in electro-magnetic operating relation to said armature, energizing circuit means including a two-position switch, for energizing said coils such that in a first position of the switch, one of the coils is energized to cause movement of the armature

against one of said abutments to effect movement of the punch member to its punching position, while in a second position of the switch, the other coil is energized to cause armature movement against the other abutment, to effect movement of the punch member from its punching position, and control means operable in response to movement of the punch member to its punching position, for effecting said second position of the switch, said control means further being operable in response to movement of the punch member from its punching position, for effecting said first position of the switch.

8. A punching device operable for effecting successive punching of a material responsive to relative movements of the device and material under punch, the device comprising a punch member including a stem having a punching end, the member being movable to and from a punching position and the stem thereof being capable of movement relative to the remainder of the member, actuating means for said punch member, a two-position control therefor, effective in one position to cause operation of the actuating means to effect movement of the punch member to its punching position, means responsive to punch member movement to said punching position, for moving said control to its other position, and control means effective in response to movement of said stem relative to the remainder of the punch member as effected by relative movement of the punching device and material while the punching end of the stem is engaged with the material punched, for causing through said control in its other position, operation of said actuating means to effect movement of the punch member from its punching position.

9. A material punching device operable for effecting successive punching of a material automatically in response to step-by-step advance of the device over the material, the device comprising a punch member including a stem having a punching end, the member being movable along a rectilinear axis to and from a punching position and the stem being capable of movement angularly relative to said axis, actuating means for said punch member, a two-position control therefor, effective in one position to cause operation of said actuating means to effect movement of said member to its punching position, said control in the other position thereof, conditioning said actuating means for operation to effect movement of the member from its punching position, and control means effective in response to angular movement of said stem produced by advance of the punching device while the punching end of the stem is engaged in the material punched, for rendering said control effective in said other position thereof, to cause operation of said actuating means to effect movement of the punch member from its punching position.

10. A material punching device in accordance with claim 9, characterized further by adjustable means for regulating said control means selectively such as to condition the same for response to greater or lesser angular movement of said stem consequent to advance of the punching device while the punching end of the stem is engaged in the material under punch.

11. A material punching device operable for effecting successive punching of a material automatically in response to step-by-step or walking advance of the punch device over the material, the device comprising a punch member including a stem having a punching end, the member being

movable along a rectilinear axis to and from a punching position, while the stem is capable of movement angularly relative to said axis, electro-magnetic means including a pair of magnet coils and a plunger operable relative to said punch member for causing movements thereof, an energizing circuit for said electro-magnetic means, including a primary and a secondary control switch, said primary control switch having first and second control positions, and being effective in the first control position, for completing the energizing circuit to one coil of said electro-magnetic means for causing said plunger to effect movement of said punch member to its punching position, means operated in response to movement of the punch member to its punching position, for actuating said primary switch to its second control position, and control means effective in response to angular movement of said stem produced by advance of the punching device while the punching end of the stem is engaged in the material punched, for operating said secondary control switch to complete the energizing circuit through said primary switch in its second control position, to the other coil of the electro-magnetic means for causing the plunger to effect movement of said punch member from its punching position.

12. A material punching device according to claim 1, wherein the means operated in response to movement of the punch member to its punching position, for actuating said primary switch to its second control position, is operable in response to movement of the punch member from its punching position, for actuating the primary switch to its first control position.

13. A material punching device in accordance with claim 11, further characterized by means for regulating said secondary control switch such as to condition the latter for operation by said control means through response of the latter to greater or lesser angular movement of said stem as produced by advance of the punching device while the punching end of the stem is engaged in the material under punch.

14. A material punching device operable for effecting successive punching of a material automatically in response to step-by-step or walking advance of the punch device over the material, the device comprising a punch member including a stem having a punching end, the member being movable along a rectilinear axis to and from a punching position, while the stem is capable of movement angularly relative to said axis, electro-magnetic means including a pair of magnet coils and a plunger operable relative to said punch member for causing movements thereof, an energizing circuit for said electro-magnetic means, including a primary and a secondary control switch, said primary control switch having first and second control positions, and being effective in the first control position, for completing the energizing circuit to one coil of said electro-magnetic means for causing said plunger to effect movement of said punch member to its punching position, means operated in response to movement of the punch member to its punching position, for actuating said primary switch to its second control position, a fixed member having a conical seat, a movable cone member seated on said conical seat and having a portion thereof relatively closely adjacent said stem, and an operating connection between said movable cone member and said secondary control switch, angular movement of said stem consequent to advance

of the punching device while the punching end of the stem is engaged in the material under punch, effecting through said cone portion relatively closely adjacent the stem, displacement of the cone member on said seat, the cone member when so displaced, acting through said operating connection to operate said secondary control switch for completing the energizing circuit through said primary control switch in its second control position, to the other coil of the electro-magnetic means, whereby to energize the same and cause plunger movement for effecting movement of said punch member from its punching position.

15. A material punching device in accordance with claim 12, wherein said fixed member having a conical seat and said movable cone member are provided with openings centrally in each, to accommodate said stem in extension therethrough, and wherein said portion of the cone member in relatively close adjacency to the stem, is constituted by an annular flange having a rounded margin relatively closely encircling the stem.

16. In a material punching device, a rod-like 25 punch member including a punch element at one end of the member, movable to and from a punching position, said punch element being movable angularly relative to the longitudinal axis of the member, actuating means including 30 a hammer for moving said member, and control

means responsive to angular movement of said punch element for causing operation of said actuating means to effect movement of the punch member from its punching position.

- 5 17. The combination and arrangement of elements as recited in claim 16, characterized further by adjustable means for regulating said control means selectively, so as to condition the control means for response to greater or lesser 10 angular movement of said punch element incident to relative movement of the punching device and the material in work, while the punch element is in engagement with the work piece.

ROBERT H. E. SCHLECHT.
